UNITED STATES PATENT OFFICE.

ROBERT L. WHITEHEAD, OF PERTH AMBOY, NEW JERSEY, ASSIGNOR TO AMERICAN SMELTING AND REFINING COMPANY, OF MAURER, NEW JERSEY, A CORPORATION OF NEW JERSEY.

ELECTROLYTIC APPARATUS.

1,206,963.

Specification of Letters Patent.

Patented Dec. 5, 1916.

Application filed February 10, 1913. Serial No. 747,253.

To all whom it may concern:

Be it known that I, ROBERT L. WHITEHEAD, a citizen of the United States, residing in the city of Perth Amboy, county of Middlesex, State of New Jersey, have invented certain new and useful Improvements in Electrolytic Apparatus; and I do hereby declare the following to be a full, clear, and exact description of the invention, such as will enable others skilled in the art to which it appertains to make and use the same.

My invention relates to certain new and useful improvements in electrolytic apparatus, and particularly to the arrangement of the electrodes in such apparatus and the connections for maintaining electric contact of an efficient character and of low resistivity throughout the system.

Prior to my invention, it has been customary in electrolytic apparatus for the deposition of metal from solutions (as, for instance, in the electro-metallurgy of copper, nickel, and the like) to arrange the electrolytic vats containing the solution to be electrolized, alongside of each other, and in such relationship that the working current entered a bus-bar, with which the anodes of the first vat of the series connected. From these several anodes, the working current then passed through the solution to the several cathodes of said vat, thereby electrolyzing the solution therein. The cathodes of the first vat, in these prior arrangements, rested upon and made electrical connection with a supporting bar, which, in its turn, supported and made electrical connection with the anodes of the next succeeding vat in the series. The main defect in this general arrangement has been that it involved a double series of electrical contacts along the common bar supporting the cathodes of the first vat and the anodes of the second vat, and so on, through the series. This difficulty is of particular importance in electrolytic apparatus, for the reason that the working current employed is of relatively low voltage, so that the total loss of energy due to the large number of individual contacts called for in an extensive installation is very considerable in amount and importance.

My present invention is intended to mini-

mize this loss of energy, first, by connecting the cathodes of the first vat of the series directly with the anodes of the second vat, 55 and so on throughout the entire installation, whereby the common connecting bar of the former arrangement may be entirely dispensed with, and the number of contacts throughout the system is reduced to one-half, and, secondly, the individual contact between a cathode and its connecting anode, or between the supply bus-bar and the individual anode, or between the exit bus-bar and the individual cathode consists of a 65 ridge or projection on the one and a recess in the other the walls of the recess coming in wedging contact with the projection or ridge on both sides thereof and clearance being provided beyond the contacting surfaces 70 whereby a highly efficient and reliable electrical connection is established and maintained.

In the accompanying drawing, Figure 1. represents a partial plan view of electrolytic apparatus embodying the preferred form of my improvements; Fig. 2. represents a transverse section thereof, partly in elevation; Fig. 3. represents, on a larger scale and in side elevation, the electric connection between the cathode of one of the vats and the anode of its neighbor in the series; Fig. 4. represents a top plan view thereof; and Fig. 5. represents a sectional view on the line 5—5 of Fig. 3. 85

Similar letters of reference indicate similar parts throughout the several views.

Referring to the drawing, A. indicates the individual members of a series of electrolytic vats, forming part of an installation 90 for electrolytic purposes, as, for instance, the deposition of metal from its solutions, by means of an electric current of low voltage. The anodes a are provided with supporting lugs b, c, for suspending them in the solution. The lugs b of the anodes rest upon the bus-bar B, which supplies the working current to the apparatus, and the lugs c rest upon an insulating strip d, as shown. The cathodes e are likewise provided with 100 lugs f, connecting them to the bar g, which is thus electrically connected with and constitutes a part of the cathode structure, and the ends of the bar g constitute the supports

from which the cathode is suspended in the solution. One end of each cathode supporting bar rests upon the insulating strip *h*, and the opposite end rests upon the supporting lug *b* of the corresponding anode in the next vat of the series.

It will be apparent, therefore, that, instead of the double set of contacts incident to the use of the common connecting bar of 10 the former arrangement herein before referred to, an electrolytic apparatus provided with my improvements has but a single set of connecting contacts between the cathodes of the several vats and the anodes of the 15 corresponding neighboring vats in the series, that is to say, the single contact established between each cathode of one vat and the corresponding anode of the next vat, so that there is a corresponding saving in energy of one half of the loss incident to the 20 usual practice.

It will be particularly noted that my preferred connection between the cathode and anode is a wedging contact. The preferred 25 form of this connection is fully indicated in Figs. 3, 4, and 5, and, as shown therein consists of a ridge or projection *i*, cast integral with the lug *b*, coöperating with a recess *j* made on the underside of a boss *k* of the 30 cathode bar *g*. This recess *j* is so related to the ridge or projection *i* that the side walls of the recess shall come in wedging contact with the sides of the ridge or projection, and, to this end, a corresponding clearance 35 is provided, as indicated in Figs. 3 and 5. The relative conformation of the ridge or projection and of the recess permits of this 40 wedging contact. In the instance illustrated, the result is attained by making the angle of the recess smaller than the angle 45 of the entering ridge or projection, but it will be understood that this is merely one of many other like or equivalent expedients for producing the same result, that is to say, of causing a binding or wedging contact on opposite sides of the ridge or projection and between said sides and the lower edges of the recess.

In so far as the wedging contact is concerned, it may, as hereinbefore indicated, 50 be made at any point, in electrolytic apparatus of this general character, where electrical connection is established, either between a cathode and anode, or between an 55 anode and the supply bus-bar, or between a cathode and the exit bus-bar, or between a cathode or an anode and a common bar electrically connecting the two as is the general practice. It will be understood, therefore, 60 that in illustrating this form of wedging contact as applied to an anode and cathode, I do not restrict myself to that particular use of the wedging contact, but intend to cover it generically in all of the other and 65 similar relationships referred to.

No claim is made to the feature of my invention involving the direct contact of the cathodes of one vat with the anodes of the neighboring vat, as that forms the subject matter of a divisional application filed by me April 17, 1916, and serially numbered 70 91,585; the claims of this application are directed to the feature of my invention which concerns the character of the contact including the provision of a wedging action 75 of one part on the other.

What I claim is:

1. An electrode for electrolytic apparatus, in combination with a coöperating conductor, the contact between the two consisting of a projection on the one and a recess in the other, the walls of the recess coming in wedging contact with the sides of the projection and clearance being provided beyond the contacting surfaces; substantially 85 as described.

2. An electrode for electrolytic apparatus, in combination with a coöperating conductor, the contact between the two consisting of a ridge on the one and a recess in the other, the walls of the recess coming in wedging contact with the sides of the ridge; substantially as described.

3. An electrode for electrolytic apparatus, provided with a ridge or projection, in 95 combination with a corresponding electrode having a recess engaging said ridge or projection; substantially as described.

4. An electrode for electrolytic apparatus, having a supporting lug provided on its 100 upper or top surface with a projecting ridge, in combination with a corresponding electrode supported upon said lug by means of a recess engaging therewith; substantially as described.

5. A cathode supporting bar consisting of a bar of conducting material adapted to extend across an electrolytic refining vat and to have a cathode suspended therefrom and a member forming a support for one 110 end of the bar, said member and said end of the bar being provided one with a recess and the other with a pair of converging walls and the said converging walls and the walls of the recess being adapted to engage 115 with a wedging contact.

6. A cathode supporting bar consisting of a bar of conducting material adapted to extend across an electrolytic refining vat and to have a cathode suspended therefrom and provided with a notch in the under side thereof extending across the bar near the end thereof, the walls of the notch being adapted to make a wedging contact with a projection forming a support for one end of 125 the bar.

7. An electrode for electrolytic apparatus in combination with a coöperating conductor, the contact between the two consisting of a recess in one and converging sides 130

of the other, the walls of the recess coming in wedging contact with said sides, and clearance being provided beyond the contact surfaces.

5 8. An electrode for electrolytic apparatus in combination with a coöperating conductor, the contact between the two consisting of a recess in one and converging sides

of the other, the walls of the recess coming in wedging contact with the said sides. 10

In testimony whereof I affix my signature, in presence of two witnesses.

ROBERT L. WHITEHEAD.
